Primary Examiner — Cynthia Ramirez*Assistant Examiner* — Michael A Maharajh(74) *Attorney, Agent, or Firm* — Gowling WLG (Canada) LLP; Neil W. Henderson(57) **CLAIM**

The ornamental design for a shuttle for a conveyor system, as shown and described.

DESCRIPTION

FIG. 1 is a top left perspective view of a shuttle for a conveyor system showing our new design.

FIG. 2 is a bottom right perspective view thereof.

FIG. 3 is a front view thereof.

FIG. 4 is rear a view thereof.

FIG. 5 is a top view thereof.

FIG. 6 is a bottom view thereof.

FIG. 7 is a left view thereof; and,

FIG. 8 is a right view thereof.

1 Claim, 8 Drawing Sheets(56)
